CLAIM

The ornamental design for a shape and letter cutting apparatus, as shown and described.

DESCRIPTION

FIG. 1 is a perspective view of the shape and letter cutting apparatus showing my new design;

FIG. 2 is a top plan view thereof;

FIG. 3 is a front elevational view thereof;

FIG. 4 is a rear elevational view thereof;

FIG. 5 is a bottom plan view thereof; and,

FIG. 6 is an elevational view taken from the right end of FIG. 3, the opposing end elevational view being a mirror image thereof.
